MOTION-PICTURE BILLBOARD

Douglas Joss, Miami, Fla.

Application November 19, 1948, Serial No. 61,049

6 Claims. (Cl. 88—18.7)

1

This invention relates to animated advertising billboards.

A main object of the invention is to provide a billboard structure, for use at a roadside or on a roof top or at some other selected city or country location, for displaying advertising messages, in the daytime and also at night.

The display in the daytime is a painted or other fixed advertisement, and means, including a movable curtain, are provided in association with this display such that when darkness comes said display is covered and a portion of the curtain on which motion pictures may be projected is substituted at the location of said display.

The curtain could be one which might be alternately raised and lowered; for instance, when the curtain is lowered, the fixed display is exposed and when the curtain is raised, the fixed display is covered and at the same time the curtain provides a motion picture screen.

As here shown, however, the curtain, by way of example, is an endless one, guided over upper and lower rollers, and the daytime advertising message is painted or otherwise carried by the curtain and so arranged thereon that when the curtain is in one position its fixed advertising message will be seen in proper location, and when the curtain is advanced for a distance equal to half its length there will be substituted for the part of the curtain carrying the fixed advertisement the other part of the curtain to constitute the motion picture screen, or there will be substituted for the last-mentioned part of the curtain its part carrying the fixed advertisement, as the case may be.

Automatic means, governed by a time clock, are provided for thus modifying the billboard for daytime and night use, and for controlling the motion picture projection, so that this last occurs only while the curtain is positioned to act as a motion picture screen. The motion pictures are preferably colored ones, and may advertise a single product, or a number of different products, successively.

The feeding of the motion picture film is not done by power drive at the projector, which latter is mounted on a suitable framework projected forwardly of the top of the billboard. Instead, the major length of the film is given a circuitous guidance within the billboard, and preferably in a chamber therein substantially of the same height and length as the billboard; thus allowing a film of very great length to be practicably handled. The film is an endless one, held to travel over sprockets and thence in various angu-

2

larly related directions through said chamber; and it is guided along and within a protective chute or tube from said chamber to and into the projector and thence from the latter along and within a second protective chute or tube from the projector back to the billboard chamber.

A feature of the invention also is a power means for moving the film through its path to and from the projector and through its billboard chamber; this means incorporating a power-drive to a sufficient number of a multiplicity of film engaging sprockets in said chamber to insure smooth steady advance of the film without drag.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is mainly a front elevation of a now favored embodiment of the invention, being also 15 a section taken on the line 1—1 of Fig. 2.

Fig. 2 is a side elevation of said embodiment.

Fig. 3 is a transverse vertical section, taken on the line 3—3 of Fig. 4.

Fig. 4 is a longitudinal vertical section, taken 20 on the line 4—4 of Fig. 3.

Fig. 5 is a fragmentary perspective, showing a common journaling means for the stub shafts of certain groups of certain of the rotatory film engaging members of Figs. 3 and 4.

Fig. 6 is a similar view, showing one of the belt connections between certain pairs of said rotatory members; the upper rotatory member in this view, and comprising a motion picture film sprocket and a pulley fixed thereto for rotation therewith, being one of the types of rotatory members pluralities of which are supported by said common journaling means.

Fig. 7 is a longitudinal vertical section, taken 35 on the line 7—7 of Fig. 3.

Fig. 8 is a diagrammatic view, showing an electric circuit, the time-clock for controlling the same, and various devices, including the curtain motor and the film feeding motor, associated with said circuit.

Referring to the drawings in detail, a suitable billboard structure is marked generally 10. The face thereof can be variously embellished as desired, and also, as in the night time, can be illuminated in any suitable or selected way, as,

for instance, by a top border of three neon tubes of different colors as indicated at 11.

A large portion of the front of the structure 10 presents an advertising area, here shown as defined by a rectangular opening 12, which may well be of the usual size of a motion picture screen, 24 feet long and 16 feet high.

The billboard 10 is here shown as comprising a main lower boxlike structure divided into three compartments 14, 15 and 16, and a superstructure 16'.

Within the front compartment 14, behind the opening 12, is the endless curtain 17, on the upper roller 18 and the lower roller 19, respectively journaled in the bearings 20 and 21. The roller 18 at each of its ends has fixed thereon a sprocket 22, and the roller 19 at each of its ends has fixed thereon a sprocket 23. Each pair of sprockets 22 and 23 is connected by a chain 24.

The roller 19 at one end has fixed thereon a pulley 25 connected by a belt 26 to the motor 27, the latter shown as mounted in the compartment 15 on a shelf 28; the wall 29 between compartments 14 and 15 having an opening 30 for passage of the belt 26.

As the curtain 17 is shown in Fig. 1, it has been positioned by the motor 27 for use of the billboard in the daytime; that is, to display, as shown, some fixed advertisement painted or otherwise suitably carried by the curtain.

As the curtain is seen in Fig. 7, the half of the curtain for use as a motion picture screen is the one here viewed. Operation of the motor 27 for changing the curtain to transfer the part thereof seen in Fig. 7, to the opening 12 of Fig. 1, and also for changing the curtain to the condition shown in Figs. 1 and 7, will be later explained; at which time also will be explained the purpose of the clock-work mechanism in the casing 31 of Figs. 7 and 8, which mechanism is operated through one cycle, by drive from the spur gear 32 fixed on the shaft 33 of roller 19, incidental to turnings of the rollers 18 and 19 to advance the curtain 17 a distance equal to exactly half the length thereof.

The billboard 10 is shown as supported on posts 34, assisted by a rear strut 35, stayed at 36.

A projector 37 is supported in proper forward elevated position by an overhead frame-work including a pair of forwardly converging angle irons 38 and a top lift guy 39.

Referring to Fig. 4, the film 40 is shown as guided serpentine fashion over a number of motion picture film sprockets 41 (see also Figs. 3 and 6). As will be noted from Fig. 4, there is ample room to lower the lower tier of said sprockets considerably, as well as ample room for placing the sprockets of each tier much closer together; so that a very great length of film 40 may be in the "magazine" provided by the compartment 16. The showing of Fig. 4 in this connection is merely diagrammatic, to keep the drawings as clear as possible.

The direction of film travel is indicated by the arrow 42 of Fig. 4, and the tube 43 at the upper left in Fig. 4 is the film return tube from the projector, while the tube 44 at the upper right in Fig. 4 is the film feeding tube to the projector. These tubes, forward of the billboard, desirably are within the angle irons 38, as indicated in Figs. 1 and 4; although not so shown in Fig. 2, which latter view, in this regard, is diagrammatic, so as more clearly to bring out the relations of the tubes 43 and 44 to the projector 37. As will be understood, the tubes are

carefully made, without abrupt curvatures; and they are preferably suitably lined to prevent film scratching.

Referring to Figs. 3-6, the various sprockets 41, and which, in the magazine compartment 16, provide what may be called the film rack, are journaled by way of their stub shafts 45 in mountings in the compartment 15. Two of these mountings are provided, one for the upper tier 10 of sprockets 41 and another for the lower tier 15 of such sprockets. Each of these mountings comprises a pair of bars 46 and 47 shaped to be laterally spaced at their upper portions when suitably secured, by way of their matching apertures 46' and 47', to the wall 48 between the compartments 15 and 16. Thus, the stub shafts 45 of the sprockets 41 of the upper and lower tiers thereof are in spaced bearings such as those marked 50 and 51 in Fig. 5.

For power drive of a sufficient number of the sprockets 41 to eliminate any drag on the film at any point along the latter, the means shown includes a pair of horizontal shafts 52 and 53 rotatable in bearings 54' and 55'. The shaft 53 is driven from the motor 54, by way of its pulley 55, the belt 56, and the pulley 57 fixed on said shaft. On said shaft 53 is also fixed the pulley 58 connected by a belt 59 to the pulley 60 fixed on the shaft 52.

Suitably spaced along the shaft 52 and fixed thereon are the pulleys 61, and suitably spaced along the shaft 53 and fixed thereon are the pulleys 62. Each of the pulleys 61 is vertically below a sprocket gear 41 which has joined thereto for rotation therewith a pulley 63 (Fig. 6); and a belt 64 connects each such pair of pulleys 61 and 63. Each of the pulleys 62 is vertically above a sprocket gear 41 which has joined thereto for rotation therewith a pulley like the pulley 63 and shown at 63' in Fig. 3; and a belt 65 connects each pair of pulleys 62 and 63'.

The various belts are engaged with the various pulleys so that all the belt driven sprockets 41 rotate in the directions required to feed the film 40 in the direction of the arrow 42.

While the pulleys 63 and 63' are shown in Fig. 3, the only one of the belts just mentioned there shown is the belt 56; in order to simplify the drawing.

If merely the number of booster-drive pulleys 61 and 62 shown are to be employed, the sprockets 41 other than those vertically above a pulley 61 or vertically below a pulley 62 need not be supplied with a pulley 63 or 63'. On the other hand, all the sprockets 41 may be supplied with the pulleys last referred to, so that at any time deemed desirable, one or more additional belts 64 and/or 65 may be added, to augment the booster action.

At 66 is indicated a time clock, as the familiar Tork time clock; the coaction of which with the apparatus of the present invention will be explained when Fig. 8 is described.

The billboard 10 will preferably be constructed of prefabricated readily movable sections, connectable by wing nuts, for quick erection and partial take-down, as when the interior of the billboard should be made accessible for inspection and repair. Adjustable flood-lights 67 are provided, for use when night repairs are to be made.

About 1,000 feet or somewhat more of motion picture film is well able to be handled. Sixteen millimeter colored film is satisfactorily used. Five to seven different animated advertisements

may be successively shown, with 150 to 200 feet of film to each advertisement.

Referring now to Fig. 8, the circuit for the curtain operating motor 27 may be traced as including the leads 68 and 69 to the motor, and thence as including the lead 70 to one contact of a switch 71, and the leads 72 and 73 from the other contact of said switch. The circuit for the film feeding motor 54 may be traced as including leads 68 and 74 to the motor, and thence as including the lead 75 to the switch 76, and thence as including leads 77 and 73.

The switch 71 is thrown to closed condition by the solenoid 78, and to open condition by the solenoid 79; these solenoids for swinging the switch arm 80 pivoted at 81. The switch 76 is thrown to closed condition by the solenoid 82, and to open condition by the solenoid 83; these solenoids for swinging the switch arm 84 pivoted at 85.

The time clock 66 is shown as including a pair of independently settable cams 86 and 87, the former fixed on the shaft 88 and the latter on the sleeve shaft 89. In accordance with the season, the cam 86 is manually set to have its lobe 90 close a normally open switch 91 at the selected hour of twilight or darkness, and the cam 87 is manually set to have its lobe 92 close a normally open switch 93 at the selected hour of dawn or daylight.

The clockwork mechanism in the casing 31 includes the cam 94, the lobe 95 of which is arranged to close the normally open switch 95 when the motor 27 has operated to move the curtain 17 through exactly half its length, following energization of this motor to move the curtain either to substitute its motion picture screen portion for its portion fixedly carrying an advertisement, to change over from daytime advertising to night time advertising, or vice versa.

Assume that night time is approaching.

In that case, the cam 86 is about to close the switch 91. Immediately this occurs, the solenoid 82 is energized, by way of the leads 68, 97 and 98, the switch 91, and the leads 99, 100, 104, and 73.

The switch 76 is thereby closed, and left closed. Closing of the switch 76, as already made plain, energizes the film feeding motor 54.

Such closing of the switch 76 also results in the energization of the neon lights 11, by way of the circuit for the motor 54 up to and including the lead 75, and thence by way of the leads 102, 103, and 73.

Also the solenoid 78 is energized, by way of the circuit including the leads 68, 97, 98, 99, 104, 105, 106, 77 and 73.

The switch 71 is thereby closed.

As soon, however, as the motor 27 has advanced the curtain exactly through half the length of the latter, now to arrange the curtain as a motion picture screen, said switch 71 will again be opened; as above explained—that is, this re-opening of the switch 71 is caused by the closing of switch 95, thereby energizing the solenoid 79, which last is in the circuit including the leads 68, 107, 108, 109, 77 and 73.

Assume that daytime is approaching.

In that case, the cam 87 would be about to close the switch 93.

Immediately this occurs, the solenoid 83 is energized, to open the switch 76; the circuit here including the leads 68, 97, 110, 111, 112, 77 and 73.

Thereby the neon lights 11 are extinguished, and the motor 54 is deenergized.

Also, the solenoid 78 is energized, again to close the switch 71 (said switch having previously been reopened, as explained in the fifth paragraph preceding); the circuit for energization of the solenoid 78 including the leads 68, 97, 110, 111, 114, 105, 106, 77 and 73.

The closing of the switch 71, as already explained, energizes the curtain changing motor 27.

As soon as such curtain change has been effected, the switch 96 is closed by the cam 94, also as previously explained; and the solenoid 79 is energized and the switch 71 once more opened, again to stop the motor 27.

While I have illustrated and described the preferred embodiment of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. An advertising apparatus comprising a billboard structure, a curtain, supporting and guiding means for the curtain whereby it may be moved, an advertising sign, means for moving the curtain to expose said sign or to hide said sign and act as a motion picture screen, and means including a motion picture projector forward of the upper part of the billboard structure for projecting motion pictures on said screen, there being an automatically operating means for periodically moving the curtain to change over from daytime to night time advertising and vice versa, and a second automatically operating means for causing motion picture film to feed to and through the projector when the curtain is moved to act as said screen and for ceasing such feed when the curtain is moved to expose said sign.

2. An advertising apparatus comprising a billboard structure, a curtain, supporting and guiding means for the curtain whereby it may be moved, an advertising sign, means for moving the curtain to expose said sign or to hide said sign and act as a motion picture screen, and means including a motion picture projector forward of the upper part of the billboard structure for projecting motion pictures on said screen, there also being an endless motion picture film for being fed through the projector, the billboard structure having a magazine chamber traversed by the film, there being means within said chamber for guiding the film therein through a circuitous path, and there being tubes between said magazine chamber and the projector through which the film is guided in passing to and from the projector.

3. An advertising apparatus comprising a billboard structure, a curtain, supporting and guiding means for the curtain whereby it may be moved, an advertising sign, means for moving the curtain to expose said sign or to hide said sign and act as a motion picture screen, and means including a motion picture projector forward of the upper part of the billboard structure for projecting motion pictures on said screen, there also being an endless motion picture film for being fed through the projector, the billboard structure having a magazine chamber traversed by the film, there being means within said chamber for guiding the film therein through a cir-

citous path, the means last-named comprising a plurality of tiers of spaced sprocket wheels.

4. An advertising apparatus comprising a billboard structure, a curtain, supporting and guiding means for the curtain whereby it may be moved, an advertising sign, means for moving the curtain to expose said sign or to hide said sign and act as a motion picture screen, and means including a motion picture projector forward of the upper part of the billboard structure for projecting motion pictures on said screen, there also being an endless motion picture film for being fed through the projector, the billboard structure having a magazine chamber traversed by the film, there being means within said chamber for guiding the film therein through a circuitous path, the means last-named comprising a plurality of tiers of spaced sprocket wheels, there being booster film advancing means in the magazine chamber, and means including a motor and connections between the motor and a plurality of said sprocket wheels whereby a sufficient number of the latter are power driven to eliminate drag on the film.

5. An advertising apparatus comprising a hollow billboard structure having a front wall formed with a central opening, a continuous flexible curtain arranged behind the central opening and having one half imprinted with advertising matter and its other half forming a movie screen, rotative means within said structure supporting said curtain for movement relative to said central opening, electrically controlled mechanism for operating said rotative means to turn said curtain to expose the half carrying the advertising matter in said central opening during the day and to expose the half forming the movie screen in said central opening during the night, a motion picture projector supported from said structure above and in front of said central opening for projecting pictures on the half of said curtain which forms the movie screen when exposed in said central opening, a film feeding tube connecting the interior of said structure to said projector, a film return tube connecting said projector with the interior of said structure, and means for feeding a continuous strip of movie

film from the interior of said structure through said film feeding tube to and through said projector and from said projector through said film return tube back into said structure.

6. An advertising apparatus comprising a hollow billboard structure having a front wall formed with a central opening, a continuous flexible curtain arranged behind the central opening and having one half imprinted with advertising matter and its other half forming a movie screen, rotative means within said structure supporting said curtain for movement relative to said central opening, electrically controlled mechanism for operating said rotative means to turn said curtain to expose the half carrying the advertising matter in said central opening during the day and to expose the half forming the movie screen in said central opening during the night, a motion picture projector supported from said structure above and in front of said central opening for projecting pictures on the half of said curtain which forms the movie screen when exposed in said central opening, a film feeding tube connecting the interior of said structure to said projector, a film return tube connecting said projector with the interior of said structure, and means for feeding a continuous strip of movie film from the interior of said structure through said film feeding tube to and through said projector and from said projector through said film return tube back into said structure, and guide means within said structure to feed the continuous film from said film return tube to said film feeding tube behind said curtain.

DOUGLAS JOSS.
